UNITED STATES PATENT OFFICE.

JOSEPHINE MOLLER, OF EAST SOMERVILLE, MASSACHUSETTS.

SIFTING-SHOVEL.

971,299.

Specification of Letters Patent. Patented Sept. 27, 1910.

Application filed December 13, 1909. Serial No. 532,924.

To all whom it may concern:

Be it known that I, JOSEPHINE MOLLER, a subject of the King of Norway, residing at East Somerville, in the county of Middlesex, 5 State of Massachusetts, have invented certain new and useful Improvements in Sifting-Shovels; and I do hereby declare the following to be a full, clear, and exact description of the invention, such as will enable others skilled in the art to which it 10 pertains to make and use the same.

This invention relates to shovels, and more especially what is preferably termed a sifting shovel.

15 The principal object of the invention is to provide an improved form of shovel which may be used for sifting ashes.

Another object of the invention is to provide a shovel of the character described with 20 a cover adapted to be folded back so that the shovel may be used as an ordinary coal shovel.

The invention further consists of certain 25 novel details of arrangement and combinations of parts hereinafter fully described, illustrated in the accompanying drawings, and specifically pointed out in the claims.

In the accompanying drawings, like characters of reference indicate like parts in the 30 several views, and:—Figure 1 is a perspective view of a shovel constructed in accordance with this invention, the cover being shown closed. Fig. 2 is a similar view with the cover shown as open. Fig. 3 is a perspective view showing the bottom of the 35 shovel. Fig. 4 is a detail section taken longitudinally of the shovel in the central plane and at the forward end thereof. Fig. 5 is a view similar to Fig. 4 showing the cover in 40 open position.

The numeral 10 indicates the bottom of the shovel which is provided with a central aperture 11 wherein is held a wire cloth 12 to form the sifter. The shovel bottom is 45 provided with upturned edges 13 preferably arranged at right angles to said bottom and having the forward edges thereof curved as shown at 14.

Rigidly secured to the back of the shovel 50 is a cover plate 15 to the forward edge of which is hinged a plate 16 having a plate 17 similarly hinged to its forward edge. The free end of the plate 17 is bent to fit over the curved portions of the sides as at 55 14 and centrally hinged on the edge of this

plate is a spring catch 18 adapted to fit into a depression 19 formed by stamping the metal of the bottom 10 at a point adjacent its forward edge. The plate 17 is preferably formed of a resilient metal so that the 60 catch may properly engage the depression 19. In order to hold the cover open the plates are so proportioned as to length that the catch 18 engages beneath the forward edge of the plate 15 when the plate 16 is 65 folded back on that plate and the plate 17 folded forward on the plate 16. The catch 18 is provided with a beaded end 20 which engages over the hinge between the plates 15 and 16, as shown in Fig. 5.

70 The shovel is further provided with the usual handle 21 having an opening 22 therein to afford means to suspend the shovel from a nail or the like.

In using this device, the ashes and cinders 75 are picked up in the shovel and the cover brought forward so that the catch 18 engages the depression 19. The shovel is then moved to and fro like an ordinary ash sifter and the ashes sifted, the cinders remaining 80 in the shovel. It is to be noted that this can be done with the shovel in the stove so that it is not necessary to carry away any of the mixed ashes and cinders but the same may be separated at the stove, the cinders re- 85 turned to the fire and the ashes alone removed.

It is further to be noted that by means 90 of the arrangement of the cover with two parts or leaves the same can be held positively open so that it will not fall forward while using the shovel as a coal shovel.

It is obvious that minor changes may be made in the form and construction of the invention without departing from the material principles thereof. It is not therefore desired to confine the invention to the exact form herein shown but it is wished to include all such as properly come within its scope.

100 Having thus described the invention, what I claim as new, is:—

1. In a device of the kind described, a shovel, a cover leaf hinged thereto, a second cover leaf hinged to the free edge of the 105 first mentioned cover leaf, and a single catch to hold said cover leaves in open or closed positions.

2. In a device of the kind described, a shovel, a cover leaf hinged thereto, a second 110

cover leaf hinged to the free edge of the first mentioned cover leaf, a catch on the free edge of the last mentioned cover leaf adapted to engage the forward edge of the shovel
5 to hold the same in closed position, and a hinge of the first mentioned cover leaf to hold the cover in open position.

In testimony whereof, I affix my signature, in presence of two witnesses.

JOSEPHINE MOLLER.
